United States Patent Office

Des. 177,997
Patented June 12, 1956

177,997

LIPSTICK CONTAINER

Henrietta P. Manville, Woodbury, Conn., assignor to Revlon, Inc., New York, N. Y., a corporation of Delaware

Application February 28, 1956, Serial No. 40,387

Term of patent 14 years

(Cl. D86—10)

FIG. 1

FIG. 4

Fig. 1 is a view in elevation of a lipstick container showing my new design;

Fig. 2 is an elevation thereof, turned 45 degrees from Fig. 1;

Fig. 3 is an elevation thereof turned approximately 45 degrees from Fig. 2; and

Fig. 4 is an end view thereof, the opposite end being identical to that shown.

I claim:

The ornamental design for a lipstick container, as shown and described.
